UNITED STATES PATENT OFFICE

171,933

STATUETTE

Christy M. Del Mas, New York, N. Y., assignor to Michael P. Grace, New York, N. Y.

Application May 4, 1953, Serial No. 24,835

Term of patent 14 years

(Cl. D29--23)

To all whom it may concern:

Be it known that I, Christy M. Del Mas, a citizen of the United States of America, residing at city, county, and State of New York, have invented a new, original, and ornamental Design for Statuette, of which the following is a specification, reference being had to the accompanying drawing, forming part thereof.

I claim:

The ornamental design for a statuette, as shown.
